UNITED STATES PATENT OFFICE.

SAMUEL S. FRETZ, SR., OF PHILADELPHIA, PENNSYLVANIA.

SELF-OPENING UMBRELLA.

1,425,761.

Specification of Letters Patent. Patented Aug. 15, 1922.

Application filed September 12, 1921. Serial No. 500,239.

To all whom it may concern:

Be it known that I, SAMUEL S. FRETZ, Sr., a citizen of the United States, residing in the city and county of Philadelphia, State 5 of Pennsylvania, have invented a new and useful Self-Opening Umbrella, of which the following is a specification.

My invention relates to a self opening umbrella or parasol which is provided with a 10 tip cup, and consists of novel means for controlling the tips and ribs to prevent spreading of the same, for controlling the runner to prevent opening of the umbrella, and novel means for releasing the tips, ribs 15 and runner to permit such opening, as will be hereinafter more fully described.

The invention is satisfactorily illustrated in the accompanying drawing, but the important instrumentalities thereof may be 20 varied, and so it is to be understood that the invention is not limited to the specific details shown and described, but I reserve the right to cover such modifications as come 25 properly within the spirit or scope of the claims.

Figure 1 represents a side elevation of an umbrella embodying my invention in closed condition.

Figure 2 represents a side elevation of the 30 frame thereof in open condition.

Figures 3, 4, and 5 represent longitudinal sections on enlarged scales of portions, certain members being in different positions in the different figures.

Figure 6 represents a transverse section 35 on line 6—6 Figure 4.

Figure 7 represents a transverse section on line 7—7 Figure 4.

Similar numerals of reference indicate 40 corresponding parts in the figures.

Referring to the drawings.

1 designates the ribs, 2 the stretchers, 3 the runner, and 4 the stick of an umbrella. In the stick which is hollow near the handle 45 is the catch 5 which consists of a bar of resilient metal held in the stick and having in its side the recess 6, the walls of which form the opposite shoulders 7, 7^x, said catch having on what will be its lower end the finger 50 piece 8 for pressing in the same, the adjacent portion of the stick having therein the slot 9 through which said portion is movable.

10 designates a disc or head which is secured to the portion of the runner towards 55 the handle of the umbrella, the same being freely encircled by a collar which forms the

slidable tip cup 11 and has connected with it the reduced sleeve 12 which is movable with said tip cup and extends towards the handle of the umbrella and has on its inner 60 end the inturned flange 13, and on its outer end the inturned flange 14, the latter being adapted primarily to enter the recess 6 and be engaged by the shoulder 7^x whereby the tip cup will be held in operative position as 65 will be hereinafter more fully referred to.

Interposed between the head 10 and the inner flange 13 of the sleeve 12 is the spring 15 which is compressed when the tip cup is in operative position encircling the tips of 70 the ribs, said sleeve being somewhat resilient.

Within the sleeve 12 is the widened tubular member 16, which is somewhat resilient and continuous of the adjacent portion of the runner and slidable therewith over the 75 stick and has on its outer end the inturned flange 17 which is adapted to enter the recess 6 of the catch 5 and to engage with the shoulder 7 of said recess, it being seen that when the umbrella is closed the flanges 14 80 and 17 occupy the recess 6 and when so disposed are controlled by the shoulders of the latter, it being seen that when the umbrella is open the parts assume the positions shown in Figure 5.

When the umbrella is closed the flange 17 of the tubular member 16 moving with the runner is caused to drop into the recess 6 and to be engaged by the shoulder 7 thus locking the runner and preventing improper 90 opening of the umbrella. The ribs are gathered with the skirt of the umbrella and the tips of the former are brought over the head 10, when the tip cup is pushed by hand towards the tips so as to encircle the latter. 95 Then the flange 14 of the sleeve 12 drops into the recess 6 of the catch and is engaged by the shoulder 7^x and thus the tip cup is held immovable, it now inclosing the tips while preventing the ribs from spreading, and the umbrella from opening. Meanwhile, the spring 15 has been compressed, as seen in Figure 3, and so the flange 14 of the sleeve is pressed against said shoulder 7^x, thus effectively retaining the tip cup in its 100 set operative position.

When the umbrella is to be opened, the catch is pressed in whereby the shoulder 7^x of the catch recedes from the flange 14 of the sleeve 12 when said sleeve is free to move 110 in the direction from the handle. Then the spring 15 is permitted to expand when it

moves the cup 11 from around the tips in the direction towards the handle and so the tips are no longer encircled and controlled and so they may spread from the head 10 and with them the ribs. Then the catch is pushed in when the shoulder 7 of the catch recedes from the flange 17 of the tubular member 16 and so no longer holds said member and the runner in locked condition. 10 Then as the member and the runner are free to move the opening spring of the umbrella (common in this class of devices, but not herein shown) is rendered operative to impart motion to the runner and consequently 15 to the stretchers and ribs, thus effecting the self opening of the umbrella.

Having thus described my invention what I claim as new and desire to secure by Letters Patent is:—

- 20 1. In a self opening umbrella, a runner, a movable tip cup thereon, a catch on the stick, and means on said catch adapted both for locking said tip cup and said runner, said means embodying a recess in said catch, 25 the opposite walls of which form shoulders for the engagement therewith of members of said tip cup and runner respectively.
2. In a self opening umbrella, a runner, a movable tip cup, a sleeve connected with the latter and slideable on the runner, said sleeve having on its outer end an inturned flange, 30

a tubular member connected with said runner and having on its outer end an inturned flange, and a catch on the stick, said catch having in its side a recess, the walls of which 35 form opposite side shoulders, said recess being adapted to receive both of said inturned flanges, one of which latter is engageable with one of said shoulders, and the other flange is engageable with the opposite shoul- 40 der.

3. In a self opening umbrella, a runner, a movable tip cup, a sleeve connected with the latter and slideable on the runner, said sleeve having on its outer end an inturned flange, a tubular member connected with said runner and having on its outer end an inturned flange, a catch on the stick, said catch having in its side a recess, the walls of which 45 form opposite side shoulders, said 50 recess being adapted to receive both of said inturned flanges, one of which latter is engageable with one of said shoulders, and the other flange is engageable with the opposite shoulder, a head on said runner within said 55 tip cup, and a resilient device interposed between said head and said sleeve of the tip cup.
